Attorney

parts as shown in Fig. 4 with a channeled portion 27 adapted to overlie rails 28 of guards 20 and 21 and similar or different portions 29 adapted to overlie or abut a rail 30 of guard 22 so that when screws 31 are extended through apertures 32 of the connectors and also through corresponding apertures in the rails 28, or even abut rails 28 and 30, the guards will be held against displacement from operative position. The ends of rails 28 may be attached to top 5, as shown in Fig. 2, as by means of screws 33.

It is apparent that when case A is opened and the top 5 is swung upwardly into vertical position, the bottom 8 swung downwardly into vertical position, the legs 15 and 16 swung downwardly, and the guards 20, 21 and 22 are swung upwardly into positions shown in Fig. 2, and said guards are connected with each other and with the top 5, the bed will be completely extended for use and the top will form a back guard while the bottom 8 forms a side support for the bed. Reversely, when the guards are detached from each other and from the top they may be readily folded into horizontal positions in the case A above mattress 13, after which the top 5 may be swung downwardly and latched. Then the legs 15 and 16 are folded into the case and the bottom is locked, following which operation the collapsed bed is in readiness for transportation to another place of use.

I claim:

1. A collapsible bed for infants comprising: a rectangular frame, a top hinged to one upper side of said frame, guards hinged to the remaining upper sides of said frame adapted to form an enclosure above the frame in cooperation with said top when folded upwardly into vertical planes, a bottom hinged to one lower side of the frame, and legs hinged to the frame opposite to the bottom, said legs and bottom forming a support of the frame when folded downwardly into vertical planes.

5 2. A collapsible bed for infants as characterized in claim 1 and in addition provided with a spring within the frame attached to the latter between the upper and lower borders of said frame, said spring being adapted to carry a mattress, said frame being so dimensioned that the spaces between the mattress and the upper border of the frame, and between the spring and the lower border of the frame, are adapted to receive the guards and legs when the same are folded into the frame.

10 3. In a collapsible bed for infants as characterized in claim 1, disconnectable joints between adjacent guards and between the top and adjacent guards effective to prevent the top and the guards being folded down when the same had been turned upwardly so as to form the enclosure.

15 4. In a collapsible bed for infants as characterized in claim 1, locking means between the frame and the bottom and between the frame and the legs preventing the same from being folded upwardly when in supporting position.

CLARE IRVING.
